UNITED STATES PATENT OFFICE.

WILLIAM C. EDWARDS AND ORVILLE R. SACKETT, OF SUSPENSION BRIDGE, NEW YORK.

APPARATUS FOR EXTINGUISHING FIRES IN RAILWAY-CARS.

SPECIFICATION forming part of Letters Patent No. 379,058, dated March 6, 1888.

Application filed May 25, 1887. Serial No. 239,353. (No model.)

To all whom it may concern:

Be it known that we, WILLIAM C. EDWARDS and ORVILLE R. SACKETT, both of Suspension Bridge, in the county of Niagara and State 5 of New York, have invented new and useful Improvements in Apparatus for Extinguishing Fires in Railway-Cars, of which the following is a specification.

This invention relates to an improved apparatus for automatically extinguishing the fire in the stove or heater of a railway-car in case of an accident to the train, and more particularly to an apparatus in which carbonic-acid gas is employed as an extinguishing agent, 15 which is generated by introducing a suitable acid into a vessel charged with water and a suitable carbonate.

The object of our invention is to provide means whereby the carbonic-acid gas is automatically generated and discharged with the water into the car-stove when the car assumes an abnormal position.

Our invention consists of the improvements which will be hereinafter fully described, and 25 pointed out in the claims.

The accompanying drawing represents a longitudinal sectional elevation of our improved fire-extinguishing apparatus.

A represents the floor of an ordinary car, 30 A' the roof, and A² one of the end walls thereof.

B represents the car stove or heater, and C the reservoir in which the gas is generated, and which is connected with the car-stove by a 35 pipe, b. The latter terminates with its lower end in the fire-pot of the car-stove and with its upper end near the bottom of the reservoir C. The latter is supported by a shelf or bracket, d, secured to the end wall, A², and is 40 filled with water and a suitable carbonate—such, for instance, as marble-dust—or any other substance which will evolve an expansive gas when combined with a proper acid. Marble-dust and muriatic acid are preferably 45 employed for this purpose on account of their cheapness. The reservoir C is provided in its upper end with an opening, c, which is closed by a screw-cap, c', and through which the reservoir is filled.

50 E represents a vessel of glass, or other fragile

or brittle material, arranged within the reservoir C and containing a suitable acid. The vessel E is supported by brackets e, secured to the inner side of the reservoir C.

f represents a horizontal pin or bolt, which 55 is arranged to slide in an opening formed in the side of the reservoir C, adjacent to the vessel E, and which projects with its outer end through a stuffing-box, f'. The horizontal bolt f is preferably provided at its inner 60 end with a head, f², which is adapted to break the acid-vessel E when the bolt is moved inwardly.

G represents a horizontal air-cylinder, which is preferably secured to the side of the reservoir C and open at its inner end and closed at its outer end. The cylinder G is provided with a piston, g, having a piston-rod, g', which projects through a bearing or opening formed in a bridge-piece or bracket, g², secured to the 70 inner end of the cylinder. The piston-rod g' is arranged in line with the horizontal bolt f, so that the inner end of the piston-rod will strike the outer end of the bolt f when the piston g is moved inwardly and cause the bolt to 75 break the acid-vessel.

g³ represents stops or projections secured to the inner side of the cylinder at a short distance from the head thereof, and which limit the outward movement of the piston.

g⁴ is a light spring which surrounds the piston-rod g', and is interposed between the piston g and the bridge-piece g², and which prevents the piston from moving inwardly and striking the bolt f under the ordinary shocks 85 or jars of the car.

The cylinder G is supplied with compressed air by a pipe, h, which enters the closed outer end of the cylinder and receives the air from a reservoir, H, arranged below the floor of 90 the car. The air-reservoir H is connected by a branch pipe, i, with the air-pipe I, which supplies the air-brakes. The pipe i enters one end of the air-reservoir H, and is provided within the reservoir with a check-valve, i', 95 which permits the air to enter the reservoir, but prevents the same from escaping therefrom through the pipe i.

The air-reservoir H is connected with the air-pipe h by a pipe, h', extending from the 100

reservoir upwardly toward the cylinder G and divided at its upper end into two branches, h^2 h^3 , which connect with the pipe h . The branch h^2 is provided with a stop-cock or valve, 5 J, and the branch h^3 with a similar cock or valve, J', whereby the flow of the compressed air from the reservoir H to the cylinder G is controlled.

k represents a depending arm or lever arranged below the stop-cock J and pivoted to a collar, k' , secured to the branch pipe h^2 . The arm k is provided at its lower end with a weight, K, which tends to hold the arm in a perpendicular position. The arm k is provided at its upper end with a gear-segment, k^2 , which meshes with a gear-segment, j , secured to the plug of the valve J, so that by swinging the arm k the plug of the valve J will be turned. The passage in the plug of 15 the valve J is so arranged with reference to the valve-casing that the valve will be closed and the air excluded from the cylinder G when the depending arm k is in a perpendicular position, while the valve will be opened and the 20 air be admitted to the cylinder G when the depending arm is moved out of its normal position.

The valve J' of the branch pipe h^3 is provided with a depending weighted arm, l , similar to the arm k , and operating the valve J' in the same manner. The depending arms k l are pivoted to swing in planes at right angles to each other, the arm k swinging lengthwise of the car and the arm l crosswise of the same.

35 When the car assumes an abnormal position by being derailed or overturned, one or both of the weighted arms k l are swung out of a perpendicular position, whereby one or both valves J J' are opened and the compressed air 40 is admitted to the cylinder G. The air entering the cylinder G forces the piston g inwardly and causes the piston-rod g' to strike the outer end of the bolt f , which latter is moved inwardly and strikes the acid-vessel E and breaks 45 the same. The acid is discharged upon the carbonate in the reservoir and generates carbonic-acid gas, which latter forces the liquid contents of the reservoir into the car stove through the pipe b and extinguishes the fire.

50 It is obvious that the piston-rod g' and the bolt f may be formed in one piece, if desired.

By effecting the mixture of the ingredients in the gas-generator by a pneumatic actuating apparatus, as described, the weights are required simply to overcome the slight resistance 55 of the air-valves, which are easily operated, and the air-pressure is used to effect the discharge of the acid into the body of the generator, whereby a considerable force is made available for this purpose, thereby insuring the prompt and efficient action of the gas-generator.

We claim as our invention—

1. The combination, with a car stove or heater, of a gas-generator provided with a fragile acid-receptacle and a discharge-pipe 65 connected with said stove or heater, an air cylinder and piston, a valve by which compressed air is admitted to said cylinder, and a rod or bolt which is operated by said cylinder and piston and which causes the breaking of 70 the acid-vessel, substantially as set forth.

2. The combination, with a car-stove and a gas-generator provided with an acid-vessel, of a bolt or rod adapted to break the acid-vessel, a piston and air-cylinder adapted to operate 75 said bolt or rod, a pipe whereby compressed air is supplied to the air-cylinder, a valve arranged in said supply-pipe whereby the admission of air to the air-cylinder is controlled, and a depending weighted arm connected with 80 said valve, whereby the valve is automatically opened when the car assumes an abnormal position, substantially as set forth.

3. The combination, with a car-stove, the reservoir C, and the acid-vessel E, of a sliding 85 bolt or hammer adapted to break the acid-vessel, an air-cylinder, G, a piston, g , arranged in the air-cylinder G and operating said sliding bolt, a pipe whereby compressed air is delivered to the air-cylinder, and a valve arranged in said supply-pipe and provided with 90 a depending weighted arm, substantially as set forth.

4. The combination, with a car-stove, the reservoir C, and the acid-vessel E, of a sliding 95 bolt, f , a piston, g , an air-cylinder, G, a brake-pipe, I, an air-supply pipe, h , connected with the brake-pipe I and delivering compressed air to the cylinder G, valves J J', arranged in the supply-pipe h and provided with depending weighted arms k l , moving at different vertical planes, substantially as set forth.

5. The combination, with the reservoir C, and acid-vessel E, arranged in the reservoir C, of a bolt, f , moving in an opening in the side of 105 the reservoir C, a cylinder, G, a piston, g , moving in said cylinder and having a piston-rod, g' , adapted to strike the bolt f , a pipe whereby compressed air is delivered to the cylinder G, a valve, J, arranged in said supply-pipe and 110 provided with a gear-segment, j , and a weighted arm, k , provided with a gear-segment, k' , substantially as set forth.

Witness our hands this 10th day of May, 1887.
